UNITED STATES PATENT OFFICE

EARL CLARENCE MILLER, OF GADSDEN, ALABAMA

ROOF COVERING

Application filed March 27, 1930. Serial No. 439,367.

This invention relates to certain improvements and refinements in the construction of roofing materials, and it has more particular reference to a novel contribution to the art which is susceptible of practical incorporation in roofing materials of the sheet roof species, the composition strip form, individual shingles of a composite texture, and rolled roofing in general.

10 The primary novelty is predicated upon two essential parts, namely, revised roofing material devised and constructed to be sold separately, plus a distinguishable retaining means for the roofing material, wherein said 15 retaining means is individualized for its utilitarian and ornamental features.

In developing and carrying the invention into effect, I have evolved and produced a structure characterized by the presence of usual and new agents which are mechanically co-related in a manner to promote expeditious 20 application and repair, compactness and convenience in arrangement, simplicity in construction, and economy in manufacture and 25 sale.

The specific details and relative association and cooperation will become more readily apparent from the following description and drawings.

30 In the drawings:

Figure 1 is a top plan view showing the principal factors of the invention with the roofing material nailed in place and the supplemental retaining device associated therewith.

Figure 2 is a longitudinal sectional view on the line 2-2 of Figure 1.

Figure 3 is a fragmentary perspective view of a portion of the strip roofing material.

40 Figure 4 is a perspective view of the novel retainer.

In the drawings, in Figure 2, the roof is designated by the reference character 5 and this is the usual sheathing. The flexible roofing material is generally designated by the reference character 6 and includes a body portion 7 the upper edge of which is nailed down as at 8. The lower edge portion is bent upon itself as at 9 and includes an underlying triangular tongue or extension 10. This

overlaps the upper edge portion of the next adjacent strip 11 as represented in Figure 2.

In accordance with the present invention, the roofing material is provided with one or more slits, each slit defining an opening as at 12 to accommodate a supplemental retainer or cleat 13. The material is so cut as to also define a shield or guard flap 14. This is here shown as of wedge-shaped configuration in general plan view.

The retainer 13 is in the form of a small metal plate including an inner end rectangular portion 15 and a projectible triangular end portion 16. The numeral 17 merely designates a hole to accommodate the fastening 65 nails 18.

In practice, the material is laid on the sheathing and nailed as at 8 and the triangular flap is turned under to overlie the next adjacent strip of material 11. Then the 70 end portion 15 of the cleat 13 is slipped through and under the flap 14 and nailed down so that the nail passes through the extension 10 and the strip 11 and into the roof 5 as shown in Figure 2. The nail hole 75 is thus arranged beneath the overhanging free end portion of the flap 13 so that it is concealed and protected against the weather.

The projectible triangular end portion 16 overlies the lower end portion of the strip 6 80 and terminates adjacent the bend 9. It provides the necessary downward retaining pressure and at the same time is exposed for its ornamental appearance.

In order to appreciate the features and advantages of this contribution, it is advisable to carefully weigh the important factors now to be mentioned. Particularly do I wish to invite attention to the fact that the fastener 13 is made separate from the roofing 85 material 6. In fact, it is nailed in place on the job. When thus nailed in position, it provides a dependable fastener and because of the triangular projectible end portion lends design to the finished roof. The invention is susceptible of being incorporated 90 in a practical manner, either in shingle roofing or in strip roofing. When employed in conjunction with the latter form of roofing, the slots 12 are provided at equi-distant 95 100

longitudinally spaced points along the lower edge of the material so as to permit this edge to be securely nailed down.

As a general rule, the sheet form of rolled roofing is in demand because of the economical properties thereof. Hence the desirability of this improvement which may be associated in a feasible manner with strip asphalt and the like.

- 10 The triangular underlying extensions 10 serve to double reinforce the anchored end of the roofing material and this is important also. Then too, the flap 14 overlies the nail hole and the fastening nail 18 so as to conceal it to remove unsightly appearance of the nail, and at the same time to protect the nail against undue deterioration from rust, and to thereby provide a more dependable leak-proof roof.
- 15 The gist of the invention, it will be understood, in contrast to prior art constructions is to provide an arrangement which is characterized by economy and to devise an efficient method of securing the exposed longitudinal edge of the roofing to the sheathing boards of the roof. This has resulted in a roofing that appears as a modification of roll roofing, the long strip making easy manufacture and affording rapid application.
- 20 Exposure of the fastening nails is eliminated entirely. Yet when it becomes necessary to replace a cleat this can be done by simply lifting up the flap and pulling out the nail and substituting a new fastener 13.
- 25 The foregoing and other features and advantages of the invention have doubtless been made plain to persons skilled in the art to which the invention relates. Therefore, a more lengthy description is regarded as unnecessary.

30 Minor changes in shape, size, materials and rearrangement of details coming within the field of invention claimed may be resorted to in actual practice if desired.

- 35 I claim:
1. In a structure of the class described, in combination, a roof, a strip of flexible roofing material nailed along its upper edge, a second strip having its upper edge underlying the lower edge of said first named strip, said lower edge of the first named strip having an inturned extension tongue overlying the top of the second named strip of material, the lower edge portion of said first named strip having a longitudinal slot formed therein, a fastening plate at the inner end portion projecting through the slot and having its outer end portion exposed and overlying the top of said first named strip, and a fastener passing through said tongue, second named strip, and into the roof for securing the plate in position.
2. In a structure of the class described, in combination, a sheet of roofing material having a longitudinal slot and a bendable

wedge-shaped flap associated therewith and defining a fastener opening, and a fastener having its inner end portion passing through the opening and its outer end portion projecting beyond the opening to overlie an adjacent edge portion of the material, the inner end portion of said fastener having a nail hole whereby said flap overlies the nail hole for protective purposes.

In testimony whereof I affix my signature. 75
EARL CLARENCE MILLER.
